UNITED STATES PATENT OFFICE.

SAMUEL S. WENZELL, OF PHILADELPHIA, PENNSYLVANIA, ASSIGNOR TO
BELLE H. HARTLEY, OF PHILADELPHIA, PENNSYLVANIA.

UMBRELLA-RETAINER FOR TRAVELING-BAGS.

SPECIFICATION forming part of Letters Patent No. 746,617, dated December 8, 1903.

Application filed February 20, 1903. Serial No. 144,309. (No model.)

To all whom it may concern:

Be it known that I, SAMUEL S. WENZELL, a citizen of the United States, residing in Philadelphia, Pennsylvania, have invented certain 5 Improvements in Umbrella - Retainers for Traveling-Bags, of which the following is a specification.

The object of my invention is to provide a valise or traveling-bag with means for carrying and retaining one or more umbrellas, canes, or the like, (referred to hereinafter for convenience simply as an "umbrella,") the retainer being, if desired, so constructed that it can be locked in order to prevent the removal of the umbrella until the bag has first 15 been opened.

In the accompanying drawings, Figure 1 is a perspective view of an ordinary form of valise or traveling-bag provided with an umbrella-holder in accordance with my invention. Fig. 2 is a transverse section, on a larger scale, illustrating the retainer for the handle end of the umbrella. Fig. 3 is a similar section illustrating the retainer for the 25 other end of the umbrella. Fig. 4 is a sectional plan view on the line *a a*, Fig. 2. Fig. 5 is a side view of the retainer shown in Fig. 2, and Fig. 6 is a view illustrating another 30 form of retainer embodying some of the features of my invention.

In Fig. 1 of the drawings, 1 represents a traveling-bag or valise of common form, and 2 and 3 represent retainers mounted thereon for the reception of the umbrella or other article to be secured to the valise.

The retainer 2 consists of a yoke composed, preferably, of bent wire and having its depending legs contained within tubes 4, forming part of a plate 4^a, which is disposed in 40 side of the bag, adjacent to one end of the same, and is retained in place upon the bag by means of the flanged screw-caps 5, said caps having stems which pass through openings in the side of the bag, near the end of the 45 same, and engage with the threaded upper ends of the tubes 4, as shown in Fig. 2, so that the material of the bag is firmly clamped between the flanges of said caps 5 and the upper ends of the tubes 4, the screw-caps being 50 tubular, so as to permit of the passage of the legs of the retainer 2. One of these legs is longer than the other and has a suitable stud

or collar at the lower end, which is acted upon by a coiled spring 6, contained in one of the tubes 4, said spring having a normal tendency 55 to depress the retainer 2 to its full extent, but permitting it to be withdrawn to any desired extent for the reception of the handle part of the umbrella, the spring retracting the retainer as soon as the same is released, so as 60 to cause it to bear firmly upon the umbrella-stick and prevent displacement of the umbrella in any direction. By withdrawing the retainer until the short leg of the same is free 65 said retainer can be turned on the long leg as a pivot, so as to be out of the way while the umbrella is being placed in position and can then be swung back into position to be retracted so as to retain the umbrella-handle.

If desired, the retainer 2 may be locked in 70 its depressed position by the engagement of the bent upper end of a retaining-lever 7 with any one of a series of notches or recesses formed in the short leg of the retainer, said lever being pivoted to the plate 4^a and acted 75 upon by a spring 8, tending to move it to locking position, the lever, however, having a projecting finger 9, which passes through a slot 10 in the plate so as to permit ready movement of the lever to unlocking position. The 80 lower end of the plate 4^a has a reversely-bent or hooked finger 11, which is passed through slits formed in the end of the bag, so as to firmly retain the lower end of the plate 4^a in 85 its proper position both vertically and longitudinally in respect to said end of the bag. (See Fig. 5.)

The retainer 3 for engaging with the outer end of the umbrella is substantially the same as the retainer 2, its long leg being contained 90 within a short tube 12, which is secured to the side of the bag by means of a screw-cap 13 in the same manner as the tubes 4, that portion of the rod within the tube being acted upon by a coiled spring 14, tending to constantly 95 depress the same, as shown in Fig. 3. The short leg of the retainer passes through an eyelet 13^a and is provided at its inner end with a stud or collar which prevents its withdrawal.

An umbrella secured to a traveling-bag by retainers such as I have described is firmly held in position on the bag and cannot be removed therefrom without first opening the

bag, longitudinal removal in one direction being prevented by engagement of the retainer 2 with the enlarged or hooked end of the handle and in the other direction by engagement 5 of said retainer 2 with the tip ends of the umbrella ribs. Hence in order to effect release of the umbrella the bag must be opened, the retainer 2 unlocked by movement of the lever 7, and then withdrawn, so as to permit retraction 10 of the retainer sufficiently to release those portions of the umbrella formerly in engagement therewith.

While I have shown a retainer 2 having a spring acting upon one leg of the same, both 15 of the legs may be thus acted upon, if desired, or springs may be dispensed with altogether if means are provided for locking the retainer in the depressed position.

In Fig. 6 I have shown a modified form of 20 the retainer, consisting of a chain 15, secured at one end to an eye 16 on the side of the bag and passing down through a tubular screw-cap 5 and tube 4^b, so that it can be tightened by pulling upon its inner free end and can 25 then be retained by engagement with a locking-lever 7^a, hung to a lug on the side of the tube 4^b and acted upon by a spring 8^a.

The attachment can be readily applied to a bag by the owner, all that is necessary being 30 to form in the side of the bag two openings near each end of the same for the reception of the screw-caps and two slits in one end of the bag for the reception of the bent portions of the retaining-hook 11.

35 Instead of the yielding retainer 3 for the outer end of the umbrella a simple loop of leather, metal, or other material may be permanently secured to the bag near one end, although a yielding retainer is preferred, be- 40 cause it readily adapts itself to the varying bulk of material which it may be called upon to retain.

Having thus described my invention, I claim and desire to secure by Letters Patent—

45 1. An umbrella-retainer for traveling-bags consisting of a pair of rigid yokes mounted upon the top of the bag, one near each end thereof, one of said yokes being capable of being drawn outwardly to permit of the insertion or withdrawal of the umbrella, substantially as specified.

50 2. An umbrella-holder for traveling-bags consisting of a rigid yoke for embracing the umbrella, said yoke having one or more legs extending to the inside of the bag, and a tubular guide in which said leg or legs of the yoke can slide, substantially as specified.

55 3. An umbrella-holder for traveling-bags consisting of a rigid yoke embracing the umbrella, said yoke having one or more legs extending to the inside of the bag, a tubular guide in which said leg or legs of the yoke can slide, and a spring for acting upon an inwardly-extending leg of the yoke so as to retract the same, substantially as specified.

60 4. An umbrella-retainer for traveling-bags,

consisting of a rod having a hooked or bent end on the outside of the bag and a stem on the inside of the bag, and a spring engaging 70 said stem, substantially as specified.

5. An umbrella-retainer for traveling-bags, consisting of a yoke having its looped portion on the outside of the bag, and a pair of depending legs on the inside of the bag, and 75 one or more springs acting to depress said yoke, substantially as specified.

6. An umbrella-retainer for traveling-bags, having a retaining portion on the outside of the bag and a portion extending to the inside 80 of the bag, and a receiver for said latter portion of the retainer consisting of a tube on the inside of the bag and a screw-cap engaging said tube and having a flange on the outside of the bag, substantially as specified. 85

7. An umbrella-retainer for traveling-bags having an adjustable member on the inside of the bag, and a locking device for retaining said member in its positions of adjustment, substantially as specified. 90

8. An umbrella-retainer for traveling-bags having an adjustable member on the inside of the bag, and a locking device, actuated in one direction by a spring, for retaining said adjustable member in its positions of adjustment, substantially as specified. 95

9. An umbrella-retainer for traveling-bags having a member extending to the inside of the bag, a receiver for said internal member, and securing means therefor comprising a 100 screw-cap at one end for engagement with the side of the bag, and a bent finger at the other end for engagement with the end of the bag, substantially as specified.

10. An umbrella-retainer for traveling-bags 105 consisting of a yoke having depending members within the bag, and a receiver for said depending members comprising a plate with a pair of tubes formed thereon, and securing devices for said receiver comprising screw-caps at one end engaging the side of the bag, and a bent finger at the other end engaging the end of the bag, substantially as specified. 110

11. An umbrella-retainer for traveling-bags 115 consisting of a yoke member having one leg longer than the other, and guides for said yoke member, from one of which guides the short leg can be withdrawn so as to permit the other leg to serve as a pivot, substantially as specified. 120

12. An umbrella-retainer for traveling-bags consisting of a yoke member having one leg longer than the other, guides for said yoke member, from one of which guides the short leg can be withdrawn so as to permit the other leg to serve as a pivot, and a spring acting on the long leg to depress the retainer, substantially as specified. 125

13. An umbrella-retainer for traveling-bags 130 consisting of a yoke member having one leg longer than the other, guides for said yoke member, from one of which guides the short leg can be withdrawn so as to permit the other leg to serve as a pivot, and a locking device

acting upon the short leg of the retainer, substantially as specified.

14. An umbrella-retainer for traveling-bags consisting of a yoke member having one leg longer than the other, guides for said yoke member, from one of which guides the short leg can be withdrawn so as to permit the other leg to serve as a pivot, a spring acting upon the long leg of the retainer to depress the same, and a locking device acting upon the

short leg of the retainer, substantially as specified.

In testimony whereof I have signed my name to this specification in the presence of two subscribing witnesses.
